UNITED STATES PATENT OFFICE.

ROBERT EDWARD LAIDLEY, OF ST. LOUIS, MISSOURI.

COLLAPSIBLE CHICKEN-COOP.

No. 911,136.

Specification of Letters Patent.

Patented Feb. 2, 1909.

Application filed December 16, 1907. Serial No. 406,728.

To all whom it may concern:

Be it known that I, ROBERT EDWARD LAIDLEY, a citizen of the United States, residing at St. Louis, Missouri, have invented a certain 5 new and useful Improvement in Collapsible Chicken-Coops, of which the following is a full, clear, and exact description, such as will enable others skilled in the art to which it appertains to make and use the same, reference being had to the accompanying drawings, forming part of this specification, in which—

Figure 1 is a perspective view of a chicken-coop constructed in accordance with my 15 invention; Fig. 2 is a perspective view of the coop collapsed; Fig. 3 is a detail sectional view taken through one of the sides of the coop; and Fig. 4 is a detail elevational view for the purpose of illustrating the 20 hinged connection between the ends and the floor of the coop and showing how the ends are folded inwardly.

This invention relates to collapsible crates, and has for its object to provide a coop of 25 simple construction that can be used for shipping chickens, said coop being so constructed that it can be collapsed after it arrives at its destination, and thus enable it to be returned to the shipper at a low freight 30 classification.

Referring to the drawings which illustrate the preferred form of my invention, A designates the floor of the coop which is preferably composed of boards held together by cross bars 1, and B and C designate, respectively, the sides and ends of the coop. The sides consist of slats 2 that are fastened to standards 3 and the ends also consist of slats 4 fastened to standards 5. The sides B are 40 connected to the floor by hinges 6 secured to the floor and to the inside faces of the lower ends of the standards 3 so that the sides can swing inwardly in the direction indicated by the arrow in Fig. 3 and thus lie on the 45 floor. The ends C are also hinged to the floor by means of hinges 7 secured to the lower ends of the standards 5 and to a bar 8 or blocks fastened to the upper side of the floor, as shown in Fig. 4, the ends being 50 adapted to swing inwardly in the direction indicated by the arrow in Fig. 4 so that they will lie upon the sides after said sides have been folded inwardly.

The top D of the coop is composed of slats 55 9 and cross bars 10, and said top is provided at its ends with depending flanges or pieces

11 that embrace or overlap the ends C of the coop when the coop is not collapsed. The top is connected to the ends by links 12 fastened to the standards 5 of the ends, and 60 hasps 13 are secured to the top and coöperate with eyes or staples 14 on the sides so that pins 15 can be inserted in said staples to retain the sides in an upright position. I prefer to use pins of the kind shown in Fig. 65 3, each of said pins having lugs 15^a that prevent the pin from being displaced from the guide 16 on the hasp in which it is mounted but permitting the pin to be raised and lowered to enter the staple or eye 14 on the 70 side of the coop.

When the coop is being used for transporting chickens the parts of the coop will occupy the position shown in Fig. 1, the sides B holding the ends C in upright position and 75 the top D retaining the sides in upright position by means of the pins 15 which engage the eyes or staples 14 on the sides. The end pieces or flanges 11 on the top which embrace or overlap the ends C of the 80 coop overcome any tendency of said ends to move outwardly and the links 12 perform the same function and also impart rigidity to the ends C.

After the coop has arrived at its destination one of the sides is dropped and the chickens are removed and both sides B are then swung inwardly so that they will lie on the floor A, the pins 15 being removed to permit the sides to swing inwardly. The ends C are 90 then folded inwardly over the sides B which lie on the floor, thus causing the top D to drop so that the parts occupy the position shown in Fig. 2, the top being locked to the floor of the coop by means of the pins 15 95 which are inserted in eyes or staples 17 on the floor. While I have herein stated that the sides are first folded inwardly and the ends thereafter folded inwardly upon the sides, it will, of course, be understood that 100 the ends and sides could be so connected or hinged to the floor that the ends would be moved inwardly first and the sides then folded inwardly upon the ends, the top of course being connected to the sides instead of to the 105 ends as herein shown.

A coop of this construction comprises few parts and is of very simple construction so that it can be manufactured at a low cost, and, furthermore, it is strong and rigid so 110 that it can be subjected to rough usage without liability of breakage.

Having thus described my invention, what I claim as new and desire to secure by Letters Patent is:

A collapsible chicken-coop comprising a floor, sides formed of slats and uprights, hinges connected to the inside faces of said uprights and to the floor in such a manner that the sides will fold inwardly, strips or blocks connected to the end portions of the floor, ends connected to said strips or blocks by means of hinges so that said ends can fold inwardly over the sides, a top formed of slats and cross pieces, links connected to said top and to the ends of the coop, flanges 15 on the top which overlap the ends of the

coop, hasps on the top which receive eyes or staples on the sides of the coop, movable pins mounted in guides on said hasps for co-operating with said staples to connect the sides and top together, and lugs on said pins which prevent them from being displaced from the guides on said hasps; substantially as described.

In testimony whereof I hereunto affix my signature in the presence of two witnesses, 25 this fourteenth day of December 1907.

ROBERT EDWARD LAIDLEY.
